Primary Examiner — Patricia A Palasik*(74) Attorney, Agent, or Firm* — Rimon PC(57) **CLAIM**

The ornamental design for a warehouse robot, as shown.

DESCRIPTION

FIG. 1 is a perspective view of a warehouse robot showing a first embodiment of the claimed design;

FIG. 2 is another perspective view thereof;

FIG. 3 is a front view thereof;

FIG. 4 is a back view thereof;

FIG. 5 is a side view thereof;

FIG. 6 is another side view thereof; and,

FIG. 7 is a top view thereof.

1 Claim, 7 Drawing Sheets(56)
